UNITED STATES PATENT OFFICE.

WILLIAM HENRY STOREY, OF SOUTHEND ON SEA, ENGLAND.

INKING ATTACHMENT FOR USE WITH TYPE DUPLICATING AND LIKE PRINTING MACHINES.

Application filed June 29, 1925, Serial No. 40,202, and in Great Britain July 1, 1924.

This invention relates to improvements in inking attachments for use with type duplicating or like printing machines.

In inking attachments hitherto employed, the attachment has, according to one type of machine, comprised a pair of side frames in which was carried a large cylinder driven through an intermediate gear by means of a gear secured to the printing cylinder. This cylinder, which received ink from the ductor, had affixed on either side cams which operated the waver or reciprocating rollers. These rollers, together with gelatine rollers, which made contact with the said cylinder were freely carried in arms which were pivoted from a stay bar which connected the side frames. Also freely carried in these arms were a set of steel rollers, superimposed, so as to make contact with the gelatine rollers. In contact with the cylinder, inked by the ductor and also the main printing cylinder, thus supplying ink to the type surfaces, was a gelatine roller carried in an adjustable manner in the above mentioned arms. Above the set of rollers and also making contact with the type faces, and driven thereby, was a gelatine roller, not in contact with any of the other rollers, carried in a bracket to which the casing or cover partly enclosing the attachment, was attached.

The inking attachment just described as well as other existing attachments have a disadvantage in that the means for regulating the amount of pressure of the inking rollers with the type faces has been somewhat inaccessible, and further, no indication of the amount or direction of adjustment has been provided. Furthermore, with some types of machines, the adjustment of the inking rollers is upset each time they are removed, and therefore they require re-setting on replacement.

Now the present invention has for its object to improve upon the mounting of the rollers which supply ink to the type faces in such a manner that the mechanism for adjusting movements of the rollers relative to the printing cylinder is readily accessible, and moreover to provide an indication of the amount and direction of adjustment of the said rollers, and further to permit of the rollers being removed from the attachment for cleaning or other purposes and to

be replaced without the adjustment having 55 in any way been altered.

The invention comprises inking rollers mounted freely upon eccentric shafts the high portions of which can be moved to or from the form on the cylinder through the 60 medium of hand operated nuts on which are indicated the necessary directions of movement, the amount of movement being apparent by the sense of feel.

The invention will now be described more 65 particularly, reference being had to the accompanying drawings whereon:

Fig. 1 is a plan view of part of the attachment showing the position of the rollers which supply ink to the type faces. 70

Fig. 2 is a side view showing part of the attachment with the milled nuts for adjusting the rollers.

Fig. 3 is a longitudinal section through one of the inking rollers. 75

Fig. 4 shows the spindle of one of the rollers.

Fig. 5 is an end view of Fig. 4.

Fig. 6 is a detail view showing one of the milled nuts with its groove or V. 80

Fig. 7 is a detail view of one of the cap pieces for enclosing the end of the milled nut.

On the drawings 22 and 22^a represent portions of the side frames of the inking attachment which is of the form described and illustrated in the specification for Letters Patent, Serial No. 39,211, filed June 24, 1925.

In the said specification, which has for 90 its object the separation of the various inking rollers from each other as well as from the type surfaces, mention is made that the type form inking gelatine rollers 41 and 42 are withdrawn from contact with the form 95 by the movement of a rack 34 in its fixed slide 35 which causes rotation of the gears 36 and 37 which rotate the eccentric spindles upon which the rollers 41 and 42 are mounted, to their high positions, so that while the 100 surfaces of the form inking gelatine rollers are out of contact with the type surfaces the gears 38 and 39 which drive these rollers from the main printing cylinder gears by means of dogs 40 may still be left in mesh 105 with the teeth of the main gear.

According to the present invention, the method of mounting the gelatine type form

inking rollers as well as the means for imparting adjustments thereto are identical for each roller although the sizes of the rollers may vary as shewn.

- 5 Referring more particularly to Fig. 3 it will be seen that the gelatine covered roller 41 is mounted on the eccentric portion of the spindle 50 by means of bushes 51 and 51^a the bush 51 being slotted to receive the free end of the dog 40 secured to the gear 38 which is driven by the main printing cylinder gear (not shewn). The said gear 38 is free to turn on a bearing 52 which passes through the side frame 22 of the inking attachment the bearing being threaded externally and secured against movement by the nut 53. The said bearing 52 is bored out for the reception of a nut 54 which in turn is bored out and slotted for the reception of the coarse threads 55^a formed on one end of the double ended screw 55. The said nut is moreover slotted as at 56 at its closed end to receive flats 57 formed at one extremity 25 of the spindle 50, the said spindle being supported at this end by the shoulder portion 58 which is housed in the bearing 52. Also housed freely in the bearing 52 is the boss 59 of the gear 36 the said gear being engaged by the rack 34 freely mounted in the slide 35 which is secured to the side frame 22 by means of the bolt and nut 60. Formed with the gear 36 is a cap piece 61 which is fashioned with a series of in-turned claws or catches 61^a for the purpose of enclosing and retaining the shouldered end of a milled nut 62. The milled nut, cap piece, gear and boss are each formed with a central bore through which 30 passes the double ended screw 55 and the screw is formed with a fine pitch thread 55^b for engagement by the milled nut 62.

The screw 55 is fashioned with a key-way 63, into which fits a key 64 which passes through a hole bored in the shoulder of the cap piece 61. The cap piece is moreover bored out to receive a spring plunger which is in the form of a ball 65 and spring 66. The inner face of the milled nut 62 is formed with a V-shape groove 67 (Fig. 6.) extending across the width thereof into which the ball 65 is forced by the spring 66 at each half turn of the milled nut. Or, more than two grooves may be formed on the shoulder portion of the milled nut. The shoulder portion 58^a at the other end of the eccentric spindle 50 has secured thereto, or formed integral therewith a milled head portion 68 a portion of which forms a journal in the side frame 22^a of the inking attachment. Pivotaly housed in a bore 69 running longitudinally with the nut is a member or pawl 70 one end of which 69^a is forced by a spring such as 71 to project

through a hole or slot formed in the journal end of the milled nut, whilst the other or free end 69^b of the pawl protrudes from the bore of the nut. The end 69^a of the pawl 70 abuts against a boss on the side frame 22^a of the attachment in such a manner that it prevents withdrawal of the eccentric spindle 50 from its supports until the free end 69^b is depressed.

From the foregoing description of the various parts of the mechanism it is to be noted that the milled nuts 62 are free to be revolved by the operator but have no end movements. Again the double ended screw 55 does not revolve relative to the gear 38 but moves endwise when the nut 62 is turned, this endwise movement causing a rotary movement to the nut 54 which imparts this movement to the eccentric spindle 50 since the end 57 thereof is journaled in the slot 56. The milled nut 62 is provided on its face with such words as "On" "Off" and arrows, the arrangement being such that when more ink is required to be applied to the type faces which are represented by the dotted curve 72 (Fig. 2) one or other, or both of the nuts 62 is or are turned in a counter-clockwise direction, i. e. in the direction of the arrow denoting "On" this action causing the roller 41 or rollers 41 and 42 to be moved into closer contact with the type faces. Moreover, each partial turn of the milled nuts 62 is made apparent to the operator because the nuts become stiff to turn directly the ball 65 under the action of the spring 66 slips into the V-shape groove 67. Again, when adjustments are made they are maintained so that when the rollers 41 and 42 are removed from the machine for any purpose replacement does not in any way interfere with the setting of the rollers because the milled nuts 62 are prevented from turning by the friction of the balls 65 in the grooves 67 and by reason of the fact that the flats 57 formed on each spindle have to enter the slots formed in the coarse pitch nuts 54 and they can only do so with eccentrics in one position relative to the slots because the flats 57 on the spindle 50 are not equidistant from the centre of the journals 58 of each eccentric shaft 50.

To remove the rollers 41 and 42 from the attachment spring 71 is compressed by pressing upon the end 69^b of pawl 70 and the end 69^a moves out of contact with the side frame 22^a. The rollers 41 and 42 are held while the eccentric spindle 50 of each is pulled out of the side frame 22^a and each roller is then disengaged from the dog 40.

Having thus described my invention what I desire to secure by Letters Patent of the United States is as follows:—

1. In inking attachments for use with type duplicating and like printing machines,

- the combination with inking rollers, eccentric spindles supporting the same, and means for operating said rollers for effecting the printing operation; of double-ended screws 5 to which end movements are afforded, a fine pitch thread on one end of each screw and a coarse pitch thread at the other end, milled nuts fitting on each of said screws and capable of being rotated but having no end 10 movements, and nuts fitting on the coarse pitch threaded ends capable of rotating on the said screws but having no end movements, the said latter nuts forming housings for the ends of the eccentric spindles sup- 15 porting said inking rollers.
2. In inking attachments for use with type duplicating and like printing machines, the combination with a cylinder, a type form carried thereby, and adjustable inking roll- 20 ers associated with said form; of means for indicating the amount of adjustments im- 25 parted to said rollers relative to said form, said means including double-ended screws, hand-operated nuts fitted on said screws and having grooves therein, cap pieces within which said nuts are fitted, and spring oper- 30 ated plungers fitted between said nuts and cap pieces and including balls and springs, said balls being engageable in said grooves.

combination with a frame, a cylinder, a type form carried thereby, and adjustable inking rollers associated with said form; of means for permitting removal and replacement of 35 said rollers without disturbing adjustments previously made between each roller and the type form, said means including double- ended screws, nuts rotatable on said screws and having slots therein, and spindles sup- 40 ported in said frame and having eccentric portions for supporting said rollers, and flattened surfaces on one end of each spindle capable of registering with the slots in said 45 nuts.

4. In inking attachments for use with type duplicating and like printing machines, the combination with a frame, inking rollers supported therein, and shafts for said inking rollers; of means permitting removal 50 and replacement of said rollers from said frame, said means including hand-operated nuts fitted to the ends of the inking roller shafts, and a spring pressed pawl contained within each nut, one end of said pawl pass- 55 ing out from the nut and abutting against said frame and the other end protruding from said nut.

In testimony whereof, I have affixed my signature.

WILLIAM HENRY STOREY.
